UNITED STATES PATENT OFFICE.

CHESTER D. AINSWORTH, OF WOLLASTON, MASSACHUSETTS, ASSIGNOR TO SEARS B. CONDIT, JR., OF BOSTON, MASSACHUSETTS.

TRIP-COIL-ADJUSTING MEANS.

1,290,863.

Specification of Letters Patent.

Patented Jan. 14, 1919.

Application filed January 4, 1918. Serial No. 210,393.

To all whom it may concern:

Be it known that I, CHESTER D. AINSWORTH, a citizen of the United States, and a resident of Wollaston, county of Norfolk, 5 and State of Massachusetts, have invented an Improvement in Trip-Coil-Adjusting Means, of which the following is a specification.

My invention relates to overload or trip coils associated with electric switches designed for the control of multi-phase circuits, and has more especial reference to the calibrating or adjusting means for such trip coils.

15 In practice, it is customary to associate with an oil switch for the use above specified, a plurality of overload coils, each having an independently movable element, adapted upon the sufficient energization of 20 said coil, to operate to cause the opening of the switch.

It has heretofore been customary to independently adjust each overload coil for the predetermined current flow at which it 25 is desired to operate.

When the trip coils are arranged for independent adjustment, it is extremely difficult to adjust the coils for substantially simultaneous operation upon an equal predetermined current flow in all coils, and consequently there is a possibility of there being one coil in the switch which will trip before the other, which is undesirable.

An object of my invention is to provide 35 a single means associated with a plurality of trip coils by the adjustment of which the entire number of trip coils may be simultaneously adjusted for a predetermined current flow.

40 The means whereby I accomplish this object of my invention is the provision of a strip or rod arranged beneath the movable elements of all of said trip coils and upon which said elements normally rest.

45 Said strip or rod is secured to an adjusting member, which may be arranged to be adjustably secured to a support, whereby said strip or rod may be moved to vary the position of the movable elements of all the 50 coils within the coils to thereby simultaneously and equally adjust the coils for operation upon a certain current flow through said coils. The support for the adjusting member may be calibrated and the adjust-

ing member may bear a witness mark to indicate on the calibration scale the current value for which all of the overload coils are adjusted to operate.

55 The overload or trip coils associated with an oil switch designed for the protection of multi-phase circuits are frequently arranged within the switch inclosing casing, and may be entirely or partially submerged in the oil contained therein. With such an arrangement it is difficult to adjust the trip 60 coils, as they are ordinarily constructed.

A second object of my invention is therefore in the provision of an overload or trip coil adjusting means whereby adjustments to the coils may be made from above the 70 surface of the oil and in a part of the switch casing that is easily accessible.

The means whereby I attain this object of my invention is in the arrangement of a portion of the adjusting member of the coils 75 above the switch supporting base or housing in the casing, whereby access to the adjusting member may be easily obtained by the removal of the switch cover.

Figure 1 is a front elevation of the trip 80 coils and adjusting means therefor.

Fig. 2 is a rear view of the apparatus of Fig. 1.

Fig. 3 is a side view of the apparatus of Fig. 1.

Fig. 4 is a top view of the apparatus of Fig. 1.

As here shown, a plurality of trip coils or solenoids 10 are secured to and suspended from a frame 11, which is secured to the 90 walls of the switch casing. Said coils or solenoids 10 depend into the oil contained in the switch casing, and are arranged to be partially immersed therein. The frame 11 is formed with a depending portion 12 and a bottom portion 13, which is provided with openings 14 therein through which the movable elements or cores 15 of the solenoids are disposed. The supporting frame thereby forms a magnetic path for the flux of the 95 solenoids, whereby the efficiency of said solenoids is increased.

The cores 15 are provided with stems or extensions 16 depending therefrom at the ends of which the striking disks 17 are secured by means of the screws 18.

The means whereby the solenoids may be equally and simultaneously adjusted for op-

eration upon a predetermined current flow comprises the rod or strip 19 secured to the end of the adjusting member 20. Said rod or strip 19 is disposed beneath all of said 5 solenoids and the movable elements of said solenoids are adapted to be supported by said rod in an unoperated condition of the solenoids. As the cores 15, through thin stems or extensions 16 are normally in con-

10 tact with the rod or strip 19, it is seen that a movement of said rod or strip in a vertical plane serves to move all of said cores equally and simultaneously in a vertical plane, to thereby vary the adjustment or 15 calibration of the solenoids.

16 The adjusting member 20, to the end of which the rod or strip 19 is secured, and which may be formed of a single strip of material, is disposed to one side of the sole- 20 noids and extends vertically upward through slots 21 in the frame supporting the sole- noids, and terminates at a point above said frame. Said slots 21 serve as guides to permit said adjusting members to be moved 25 in a substantially vertical plane to corre- spondingly adjust the solenoids and main- tain said adjusting member in alinement in any adjusted position.

26 A standard 24 is secured to the top mem- 30 ber 12 of the solenoid supporting frame and is arranged adjacent the top portion of the adjusting member, and said adjusting mem- ber is adapted to be moved over the face of said standard in an adjustment of said mem- 35 ber.

36 Said standard 24 is formed with a slot 23 therein, in which the bolt of a wing nut 22, is disposed. Said bolt is secured to the top portion of the adjusting member and forms 40 means, in conjunction with the standard 24, whereby the adjusting member may be clamped in any adjusted position.

45 Inasmuch as the end of the adjusting member extends above the solenoids, it is above the surface of the oil in which the solenoids are adapted to be either partially or entirely immersed, so that changes of 50 calibration for the solenoids may be easily and conveniently made.

51 The face of said standard 24 may be formed with a scale 25, which may be cali- brated in amperes, and the top edge 26 of the adjusting member may be employed as a witness mark which, in conjunction with 55 the scale on said standard, serves to indicate the value of current at which all of said coils are adjusted to operate.

I claim:

56 1. In combination with a plurality of trip 60 coils for electric switches, of a single means arranged to simultaneously adjust said coils for a determined current flow.

65 2. In combination with a plurality of trip coils, of a single means arranged to simul- taneously adjust the movable elements of

said coils for a determinate current flow, said means extending above the surface of oil within said switch.

3. In combination with a plurality of trip 70 coils for electric switches, of means in nor- mal engagement with all of the movable ele- ments of said coils, whereby a movement of said means causes a corresponding move- ment of said elements.

4. In combination with a plurality of trip 75 coils for electric switches, of a single means in normal engagement with all of the mov- able elements of said coils, whereby a move- ment of said means causes a corresponding move- ment of said elements. 80

5. In combination with a plurality of trip coils for electric switches, of a rod extended beneath all of the movable elements of said coils and with which said movable elements are in normal engagement, and adjusting 85 means for said rod.

6. In combination with a plurality of trip 90 coils for electric switches, of a rod extended beneath all of the movable elements of said coils and with which said movable elements are in normal engagement, adjusting means for said rod whereby said coils are adjusted for a determinate current flow, and means to indicate the adjustment.

7. In combination, a plurality of trip coils, 95 a supporting frame therefor, movable ele- ments arranged within said coils, a rod ar- ranged beneath all of said movable elements and with which said elements are in normal engagement, an arm secured to said rod and 100 slidably arranged to said supporting frame and means to secure said arm and rod in adjusted position to said frame.

8. In combination, a plurality of trip coils, 105 a supporting frame therefor, movable ele- ments arranged within said coils, a rod ar- ranged beneath all of said movable elements and with which said elements are in normal engagement, an arm secured to said rod and 110 slidably arranged to said supporting frame, a standard arranged on said frame and with which said arm is in sliding engagement, and means whereby said arm is secured in adjusted position to said standard.

9. In combination, a plurality of trip coils, 115 a supporting frame therefor, movable ele- ments arranged within said coils, a rod ar- ranged beneath all of said movable elements and with which said elements are in normal engagement, an arm secured to said rod and 120 slidably arranged in said supporting frame, a standard arranged on said frame and with which said arm is in sliding engagement, means for indicating the current adjustment of said trip coils, and means whereby said 125 arm is secured in adjusted position to said standard.

10. In combination, a plurality of trip 130 coils, a supporting frame therefor, movable elements arranged within said coils, a rod

arranged beneath all of said movable elements and with which said elements are in normal engagement, an arm secured to said rod and slidably arranged in said supporting frame, a standard arranged on said frame and with which said arm is in sliding engagement, a calibration scale on said standard operating, in conjunction with the end of said arm, to indicate the current ad-

justment of said coils, and clamping means 10 for said arm.

In testimony whereof I have signed my name to this specification in the presence of two subscribing witnesses.

CHESTER D. AINSWORTH.
